UNITED STATES PATENT OFFICE.

JOHN SHARPE, OF GRAVENHURST, CANADA.

TURBINE WATER-WHEEL.

SPECIFICATION forming part of Letters Patent No. 624,692, dated May 9, 1899.

Application filed August 6, 1898. Serial No. 687,950. (No model.)

To all whom it may concern:

Be it known that I, JOHN SHARPE, of Gravenhurst, in the Province of Ontario and Dominion of Canada, have invented a new and Improved Turbine Water-Wheel, of which the following is a full, clear, and exact description.

The object of my invention is to provide a turbine water-wheel which will be of exceedingly simple, durable, and economic construction and through the medium of which power may be obtained with a less amount of friction than in the ordinary construction of such machines.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a vertical transverse section taken substantially on the line 1 1 of Fig. 3. Fig. 2 is a plan view of the machine, the bridge 25 located over the gearing being broken away. Fig. 3 is a side elevation of the machine, portions thereof being in vertical section. Fig. 4 is a horizontal section taken substantially on the line 4 4 of Fig. 3. Fig. 5 is a side elevation of one of the feed-pipes; and Fig. 6 is a vertical section through one of the feed-pipes, illustrating the manner in which the cut-offs operate therein.

A represents a tank adapted to receive water, which tank is supported by pillars 10 upon a foundation B, in which foundation a well or tail-race C is formed, having a suitable outlet C'.

The tank A is provided with a central opening 11, extending through it from top to bottom, the opening being surrounded by a suitable wall, and the tank is supplied with water from two flumes 12 and 13. Each flume is connected with a box-casing 14, and the said box-casings are connected with and extend above the tank, and waterways are provided in the lower portions of the box-casings, whereby the water may pass from the flumes into the tank. A gate 15 is mounted to slide 45 in each box-casing, the casings extending sufficiently above the tank to accommodate the gates when elevated. Each gate 15 is prefer-

ably made hollow and is provided with a hollow stem. The gates are provided with beveled lower ends so arranged that the water in 55 the flumes 12 and 13 bears against said ends and tends to raise the gates. Two stems are ordinarily employed for each gate, and the stems extend upward through suitable openings in a guide-bar 17, secured transversely 60 to the flumes, the said guide-bar extending along the inner faces of the flumes from one to the other. A truss or lift-bar 18 is located above the bar 17. The truss or lift-bar is provided with openings which loosely receive 65 the upper ends of the stems 16 of the gates, the stems being provided with flanges 19 at their upper edges. The gates are raised and lowered through the medium of a shaft 20, which is provided with a double thread and 70 is held to turn in a threaded eye in the truss or lift-bar 18 and in a lug 21, extending from the tank A between the flumes, as shown in Fig. 2. The shaft is operated through the medium of a hand-wheel 22, which is securely 75 fastened to the shaft, as shown in Figs. 1 and 2.

Between the tank A and the foundation B a casing D, preferably circular, is made to rest upon the foundation over the tail-race C. This casing is made, preferably, in two sections, an upper section 23 and a lower section 24, the lower section being open at top and bottom and the upper section being closed at the top and open at the bottom, as shown in Fig. 3. A series of feed-tubes 25 is connected 85 with the bottom of the tank A, having communication with the interior of the tank, the feed-tubes being circularly arranged, and the said feed-tubes at their lower ends are in communication with the interior of the upper 90 section of the casing D, and within the upper section of the casing D, between the bottom portions of the various feed-tubes, guide or deflecting blocks or plates 26 are located, the said guides or conductors 26 having their 95 lower ends pointed and curved all in the same direction, the pointed portions of the guides being substantially horizontal.

Two cut-offs 27 are located, preferably, in each feed-pipe, as shown in Fig. 6. These 100 cut-offs are in the nature of dampers and when brought to a diametrical position, as shown in positive lines in Fig. 6, entirely cut off communication from the upper to the lower por-

- tions of the feed-pipes, the abutting edges of the cut-offs being beveled, as shown at 27^a. When the cut-offs are opened, they stand vertically or longitudinally of the feed-pipes, as shown in dotted lines in Fig. 6. Each cut-off is attached at or near its center to a spindle 28, and these spindles are journaled in opposite sides of the feed-tubes, one spindle of each tube at its outer end being provided with a segmental gear 29 and the other with a corresponding and meshing gear 30, as shown in Fig. 5, the gear 30 having a handle 31. Through the medium of these segmental gears the cut-offs are opened and closed as desired.
- 15 A wheel E is mounted to turn in the lower section 24 of the casing D, and the said wheel is provided with peripheral buckets e, and the series of peripheral buckets are substantially vertical at their upper ends, being inclined more or less from the vertical at a point slightly below their opposite ends to the lower edge of the wheel, the inclination of all of the buckets being in the same direction. The guides 26 are adapted to direct the water 20 passed through the feed-tubes into the buckets e, and therefore act in the capacity of conductors.
- The wheel E is secured upon a vertical shaft 32, mounted to turn in a suitable bearing 33, erected on a foundation 34 in the center of the tail-race C. The shaft 32 extends upward through the opening 11 in the tank and through a spider 35, which tends to strengthen the tank at its open portion. The 35 upper end of the shaft is made to turn in a bridge-piece 36, attached to bearings 37, erected at opposite sides of the opening in the tank, and in each of the said bearings the inner end of a drive-shaft is journaled, the shafts being 40 designated, respectively, as 38 and 39. The shafts are likewise journaled in suitable boxes located near the outer edges of the tank. Each shaft is provided with a pulley 40 at its outer end.
- 45 The wheel-shaft 32 is provided with a beveled gear 42 near its upper end, and the said beveled gear meshes with pinions 41, one of which is attached to the inner end of each shaft 38 and 39. After the cut-offs in the 50 feed-pipes have been set they may be so locked through the medium of a latch 32^a. (Shown in Fig. 5.)
- The object of making the gates and their stems hollow is to admit of their being readily raised and to reduce the weight of metal, and, furthermore, the stems are made hollow in order to afford access of air to the gates and allow the expansion and contraction of the air according to the changes in the temperature.

Having thus described my invention, I claim as new and desire to secure by Letters Patent—

1. In a turbine water-wheel, the combination, with a tank, a wheel supplied with water from the said tank, means for regulating the supply of water from the tank to the said wheel, and a shaft driven by the said wheel, of flumes, hollow gates located between the flumes and the tank, hollow stems connected with the said gates, guides for the stems, and means substantially as described, for simultaneously raising and lowering the gates, for the purpose set forth.

2. In a turbine water-wheel, the combination, with a tank having a walled opening at its center, flumes connected with the said tank, gates located between the flumes and the tank, an adjusting device, and a connection between the adjusting device and the 80 said gates, of a casing located below the tank, a wheel mounted to rotate in the said casing, provided with radial buckets, the upper ends whereof are straight and the lower and central portions downwardly inclined, feed-tubes 85 connected with the tank and extending within the said casing, cut-offs located within the said feed-tubes, and means for operating the cut-offs from the exterior of the tubes, and conductors located between the feed-tubes, 90 extending within the said casing, the said conductors being curved at their lower edges and located over the buckets of the wheel, substantially as described.

3. In a hydraulic motor, the combination 95 of a water-tube, two cut-offs mounted in said tube to command the same, a gear in connection with each cut-off, the gears meshing with each other to synchronize the movements of the cut-offs, and a latch mounted 100 adjacent to the gears and capable of moving between the same to lock the gears from movement.

4. In a hydraulic motor, the combination 105 of a tank, two flumes leading to the tank, a casing carried by each flume, the casings respectively communicating with the flumes, a gate commanding each flume, the gates being respectively movable into the casing to open the flumes, a stem in connection with 110 each gate, a guide-bar extending between the casings and having the stem passed through them, a lift-bar in connection with the stems of the gates, and means for raising and lowering the lift-bar to operate the gates.

JOHN SHARPE.
